(57) **CLAIM**

The ornamental design for a multi-sided container with multiple compartments as shown and described.

DESCRIPTION

FIG. 1 is a top perspective view of a multi-sided container with multiple compartments of the present invention showing our new design;

FIG. 2 is a bottom perspective view thereof;

FIG. 3 is a top plan view thereof;

FIG. 4 is a bottom plan view thereof;

FIG. 5 is an elevational view thereof; and,

FIG. 6 is another elevational view thereof.

The broken lines shown in the drawings depict portions of the multi-sided container with multiple compartments that form no part of the claimed design.

1 Claim, 6 Drawing Sheets
